2 SHEETS—SHEET 2.

UNITED STATES PATENT OFFICE.

HUGO GERNSBACK, OF NEW YORK, N. Y., ASSIGNOR, BY MESNE ASSIGNMENTS, TO THE MOTOR CAR EQUIPMENT COMPANY, OF NEW YORK, N. Y., A CORPORATION OF NEW YORK.

INCANDESCENT LAMP.

No. 902,069.

Specification of Letters Patent.

Patented Oct. 27, 1908.

Application filed March 12, 1907. Serial No. 362,051.

To all whom it may concern:

Be it known that I, HUGO GERNSBACK, a subject of the Grand Duchy of Luxembourg, and a resident of the city, county, and State 5 of New York, have invented certain new and useful Improvements in Incandescent Lamps, of which the following is a specification.

My invention relates to incandescent electric lamps such as are commonly used for 10 electric lighting, and especially those used for automobiles, boats, etc., where storage batteries are used, and where it is desired to attach an electric lamp in a gas lamp whereby the lamp may be interchangeably gas or 15 electric.

I provide a lamp which is so made that no light is wasted by side reflection when used for autos and the like, and wherein a light of sixteen candle power may be burned from an 20 ordinary storage or chemical battery having a very low voltage. Instead of requiring 106 or 110 volts, my improved lamp will produce a 16 candle power light for headlight purposes, from the ordinary batteries carried by 25 automobiles, boats, etc. Heretofore only small lights could be worked from such batteries, and motorists have been compelled to rely generally on acetylene as a headlight illuminant.

30 Another result of my improvement is that there are several filaments and one or more may burn out and the lamps will burn as long as there is one filament remaining. This is highly important in uses for which my lamp is adapted. The light, it will be understood, 35 is reduced when a filament is burned out, but there will be some light until the last filament burns out. This feature is also important in burning lamps in series.

40 My improved lamp when many are used, may be strung in series or parallel and are equally adapted for both purposes.

In the drawings forming part of this application, Figure 1 is a front elevation of a gas 45 headlight or searchlight with my improved electric lamp applied thereto. Fig. 2 is a partial sectional view of a lamp with my improvements. Fig. 3 is a perspective view showing the preferred form of filament and 50 feed wire. Fig. 4 is a similar view showing a slightly different disposition of the filaments. Fig. 5 is a still different form for the filaments. Fig. 6 is a front elevation with parts broken away, making it substantially a sectional

view. Fig. 7 is a section on the line 11—11 55 of Fig. 6, and Fig. 8 is an inverted plan view of the plug.

The lamp has the usual characteristics of the ordinary incandescent lamp, such as a sealed globe with a vacuum created therein, 60 and the form of the filaments may be changed without departing from the spirit of the broad claims.

My improved lamp or bulb I have shown attached to an ordinary automobile gas 65 lamp 1, so as to provide an interchangeable means for using gas or electricity as the illuminant. The lamp which may be of any well known form, is provided with a standard 2 and supporting arms 3 to which the body 5 70 of the lamp is pivoted at the point 4. The pipe 6 through which the gas is usually supplied to the point of combustion, is provided with an end 7 which is exteriorly threaded and the gas tip is usually screwed thereon. 75 In using the lamp as an electric lamp the tip is removed and my improved electric lamp is substituted. This consists of a neck 30, which is interiorly threaded so as to fit the end 7 of the pipe 6. This neck is part of a 80 socket 30^a, in which there is an aperture 27, through which the electric feed wires 25 and 26 pass, so as not to interfere with the gas pipe, and so as to require no fitting except to the independent socket. Secured to the lower 85 portion 30^a is a casing 30^b which incloses the seal and connections of the lamp, and at the top is provided with a neck 9 having an insulation 33. Within the casing is a metal 90 socket 32 formed with a threaded interior in which the corresponding end 12 of an electric lamp is screwed. A set screw 11 is provided in the neck 9 which prevents the lamp from working out of its socket with the continuous jarring.

95 The electric lamp consists of an interior sealing material 34, of plaster or the like, in which there is a glass seal 14 for the feed wires 15 and 16. The globe 31 of the lamp is fitted in the rim of the part 12 so as to be 100 air tight, and it may be of any desired shape. Running through the glass seal 14 are the supply wires 15 and 16 which are made of platinum or any of the materials suitable for such purposes, and these are connected at 105 their lower ends one to the part 12 and the other to the end of the glass seal 17 so as to come in contact with the connecting plate

which connects with the wire 26 and which is secured by a screw 24. There is a similar connecting plate 23 which forms an electrical connection between the wire 25 and the part 12.

In all the forms shown the filaments are to be inclosed in a globe, but for simplicity of illustration the globe is not shown in all views.

10 In the form shown in Figs. 1, 2, 3, and 6, the feed wires 15 and 16 extend upwardly into the globe 31 and terminate near the top where they are preferably connected by a stiffening non-conductive bar 20, of glass or 15 other material. A similar connection 19 is provided near the lower part, so that the wires are thus made more rigid without forming an electrical connection. Between the feed wires I provide a number of filaments 21 connected to the supply wires at the points 22 and these filaments are adapted to burn in parallel and simultaneously.

With the filaments arranged in Fig. 3, the light is economical for lamps such as shown 25 in the drawings, where it is desired to throw the light directly ahead. The light is thrown in two directions, forward and backward, the backward being reflected forward by the reflectors, and very little is wasted by side reflection.

30 If it is desired, the filaments 35 may be arranged in zig-zag form between the feed wires, as is shown in Fig. 4, they being ar-

ranged to burn in parallel; or they may be arched 36 as shown in Fig. 5.

The lamps made according to my improvements may themselves be connected on wires so as to burn in parallel or in series; the filaments in all cases burning in parallel and simultaneously, as herein described.

A vacuum is created in the lamp when it is sealed and it otherwise has the characteristics of an electric incandescent lamp.

Having described my invention, what I claim is:—

1. An incandescent electric lamp having a globe, a plurality of metallic feed wires extending into the globe, a plurality of filaments connecting said feed wires and adapted to burn in parallel and simultaneously, and a non-conductive stiffening member connecting the said feed wires.

2. An incandescent electric lamp having a globe, a plurality of metallic feed wires extending into the globe, a stiffening member of non-conductive material connecting the said feed wires and a plurality of filaments connecting the feed wires between the said stiffening members and adapted to burn in parallel and simultaneously.

Signed this 11th day of March, 1907.

HUGO GERNSBACK.
